UNITED STATES PATENT OFFICE

171,718

GAME BOARD

Lorrell C. McFarland and Tracy W. Reese,
Claremore, Okla.

Application October 5, 1953, Serial No. 27,074

Term of patent 7 years

(Cl. D34—5)

To all whom it may concern:

Be it known that we, Lorrell C. McFarland and Tracy W. Reese, citizens of the United States of America, residing at Claremore, in the county of Rogers and State of Oklahoma, have invented a new, original, and ornamental Design for a Game Board, of which the following is a specification, reference being had to the accompanying drawing, forming part thereof.

Figure 1 is a plan view of a game board, showing our new design, and

Figure 2 is an edge view thereof.

The drawing is shaded to illustrate contrast of color.

We claim:

The ornamental design for a game board, as shown and described.

LORRELL C. MCFARLAND.
TRACY W. REESE.
